OSMON B. CAMPBELL, JR., OF ST. JOSEPH, MISSOURI.

APPARATUS FOR PUMPING FLUID.

1,222,601.

Specification of Letters Patent. Patented Apr. 17, 1917.

Continuation of application Serial No. 25,420, filed May 3, 1915. This application filed August 9, 1916. Serial No. 113,947.

To all whom it may concern:

Be it known that I, OSMON B. CAMPBELL, Jr., a citizen of the United States, residing at St. Joseph, in the county of Buchanan 5 and State of Missouri, have invented certain new and useful Improvements in Apparatus for Pumping Fluid; and I do declare the following to be a full, clear, and exact description of the invention, such as will enable others skilled in the art to which it 10 pertains to make and use the same, reference being had to the accompanying drawings, and to the letters and figures of reference marked thereon, which form a part of this 15 specification.

My invention relates to an apparatus for pumping fluid, and has for its principal object the utilization of expansive force in a hydro-carbon or like engine and hydro- 20 static force of the pumped liquid for the efficient, convenient and economical transmission of liquid.

More particularly my apparatus comprises the utilization of vacuum or partial 25 vacuum resulting from the momentum or impulse that follows each pumping stroke, to draw in liquid to the line or conduit above the pump piston, and utilization of the hydrostatic force of liquid in the 30 line or conduit to return the pump piston and compress an intaken charge in the combustion chamber of the engine cylinder.

In accomplishing these and other objects 35 of the invention, I have provided apparatus, the preferred form of which is illustrated in the accompanying drawings, to which reference is made by reference numerals in the specification.

In the drawings, 1 designates an engine, 40 which may be of any suitable hydro-carbon type, having a two-cycle operation and comprising a cylinder 2 and a piston 3 that divides the interior of the cylinder into an outer supply chamber 4 and an inner comp- 45 bustion chamber 5.

Opening into the outer end of the supply chamber 4 is an intake conduit 6, whereby charges of fuel may be delivered to the supply chamber, and having a back check valve

7 for retaining the charge within the chamber. 50

Leading from the outer end of the combustion chamber 5 is a cleaning or scavenging conduit 8, and leading from the outer end of the supply chamber to the outer end 55 of the combustion chamber is a feed conduit 9, through which compressed fluid may pass from the supply to the combustion chamber of the cylinder; the said conduit 9 containing a back check valve 10 for preventing 60 back flow to the supply chamber.

The engine also includes an ignition device 12, of any suitable type, and the piston 3 is provided with a baffle 13.

Attached to the inner head 15 of the engine cylinder is a conduit 16, which may extend into a well or to the point from which liquid is to be pumped, and preferably comprises at its inner end a pump cylinder 17, having open communication, through the 70 port 18, with the interior of the conduit 16. In the specific construction shown in the drawings, the conduit 16 has flanges 19 and 20 at its opposite ends, whereby the conduit is attached to the engine and pump 75 cylinder heads.

Extending through stuffing boxes 23—24 on the outer and inner heads of the engine cylinder, and through the engine piston 3, is a rod 25, which is fixed to the engine piston and extends through the pump conduit 16 into the pump cylinder 17, where it is rigidly secured to a pump piston 26 that operates in the cylinder 17. 80

The pump piston 26 contains an automatic valve, preferably including the port 27 in the piston and a plug 28 that operates in said port and is adapted for lifting to permit liquid to flow from a well or source of supply to the inner chamber of the pump 90 cylinder, and is arranged to close to trap liquid within said chamber.

Opening from the conduit 16 is a main 95 that may extend to any suitable point relative to the operative portion of the apparatus, and through which the liquid is conducted to a delivery point, the main being in open communication with the pump con-

duit, and the entire line of flow through the main and pump conduit being unobstructed, in order to facilitate the outward flow of liquid and permit back flow of the liquid to 5 the pump piston after a functional movement of the piston. The hydrostatic force of the back flowing liquid is utilized to return the pump and engine pistons to effect the admission of a charge of fuel mixture to 10 the supply chamber, and the compression of a previously admitted charge in the combustion chamber of the engine cylinder.

In using the apparatus, liquid having been admitted to the liquid cylinder 15 above the liquid piston 26 and passed to the liquid conduit 16, is forced upward in the said conduit by the piston 26 in said liquid cylinder, which piston receives its motion from its connection by the rod 25 with the 20 power piston 3, which piston is lifted by the combustion and expansion of the gases in the combustion chamber 5. Considerable momentum is imparted to the rising column of liquid in the liquid conduit 16, and said 25 liquid continues to rise in said conduit after the pistons above mentioned have come to rest, and as long as said liquid continues to rise, other liquid enters said liquid cylinder through the inlet valve port 27, and passes 30 to the liquid conduit. When the momentum previously imparted to the liquid in the liquid conduit is spent, and the said liquid comes to rest, the liquid inlet valve 28 closes, said liquid descends in said conduit 35 and in said liquid cylinder against the piston 26 in said liquid cylinder, and forces said piston downward. When said piston 26 descends it draws downward the above mentioned engine piston 3 in the above men- 40 tioned engine cylinder 2, by connection with said engine piston by the rod 25, and compresses the charge of combustible mixture in the combustion chamber of the engine. When said combustible mixture has been 45 ignited and has burned, upward motion is again imparted, through piston 3, rod 25, and piston 26, to the liquid in the liquid cylinder, and in the liquid conduit by the explosive impulse attending said burning.

50 The engine portion of this machine operates on the well known two-cycle principle, and it is apparent that successive charges of combustible mixture are compressed by the return movement of the pump piston under 55 hydrostatic force of the liquid, and when burned, lift the pistons to impart upward impulses to the liquid column in the conduit, thereby reciprocating the pistons to produce the two-cycle operation of the engine and effect the pumping.

The foregoing specification and the accompanying drawing show one mechanical arrangement by which the spirit of this in-

vention may be put into practice, and are for the purpose of making clear the operation 65 of the invention and the action of the forces used, and I do not limit the scope of this invention to such particular details of structure.

Having thus described my invention, what 70 I claim as new therein, and desire to secure by Letters-Patent, is:—

1. In a liquid pumping apparatus, a liquid conduit having a valved inlet near its lower end, a liquid pump, and an engine of 75 the internal combustion, two-cycle type, in such operative relation that an explosion occurring in the combustion chamber of the engine will impart upward motion and impetus to liquid in the conduit, and that 80 gases passed to the combustion chamber of the engine will be compressed therein by the descent of liquid through the liquid conduit into the liquid pump.

2. In a liquid pumping apparatus, a 85 liquid conduit open at its upper end and having a valved inlet near its lower end and comprising a liquid cylinder member at its lower end, a piston in the liquid cylinder, an engine of the two-cycle, internal-combustion 90 type, a piston in the engine cylinder, and a rod connecting said pistons, one end of the liquid cylinder being in communication with the lower portion of the liquid conduit and the other end being open, whereby gases 95 expanding in the engine cylinder impart upward motion to liquid in the liquid conduit and gases passed to said engine cylinder are compressed therein by force of liquid passing down the liquid conduit and into the 100 liquid cylinder against the piston in said liquid cylinder.

3. In a liquid pumping apparatus, an engine of the two-cycle, internal combustion type, comprising a cylinder and a piston, a liquid cylinder open at its lower end, a liquid conduit spacing and attached to said cylinders, the said conduit being in open communication with the liquid cylinder, a piston in the liquid cylinder, a rod extending through said conduit and connecting the engine and liquid pistons, and a check valve controlling flow to the conduit above the liquid piston, the liquid conduit having an opening therein for the discharge of liquid. 115

4. In a liquid pumping apparatus, a liquid conduit, an engine of the two-cycle, internal combustion type comprising a cylinder and piston, mounted on said conduit, an open bottom liquid cylinder suspended 120 from said conduit, and having open communication with said conduit at its upper end, a piston, a rod extending through said conduit and connecting the piston in the liquid cylinder with the piston in the engine cylinder, a check valve for passing liquid to 125

the liquid cylinder above the liquid piston, the said conduit having a discharge opening above the liquid piston.

5. In a liquid pumping apparatus, an engine of the two-cycle, internal combustion type, comprising a cylinder and a piston, a liquid conduit having its upper end attached to the cylinder head, a liquid cylinder attached to the lower end of said conduit, the lower end of said liquid cylinder being open

and the upper end in open communication with the conduit, a piston in the liquid cylinder, a rod extending through the conduit and connecting said pistons, a check valve in the liquid piston for passing liquid 15 to the conduit, the liquid conduit having a discharge opening between the engine and liquid cylinders.

In testimony whereof I affix my signature.
OSMON B. CAMPBELL, JR.
